UNITED STATES PATENT OFFICE.

PIERRE CAUHAPÉ, OF DETROIT, MICHIGAN.

PILL PACKING-BOX.

SPECIFICATION forming part of Letters Patent No. 259,364, dated June 13, 1882.

Application filed February 21, 1882. (No model.)

To all whom it may concern:

Be it known that I, PIERRE CAUHAPÉ, of Detroit, in the county of Wayne and State of Michigan, have invented new and useful Improvements in Pill Packing-Boxes; and I do hereby declare that the following is a full, clear, and exact description thereof, reference being had to the accompanying drawings, which form a part of this specification.

10 The nature of this invention relates to certain new and useful improvements in pill packing-boxes, as more fully hereinafter described.

The invention consists in a packing-box especially adapted for holding capsules, and subdivided into cells or channels of proper size for different sizes of capsules by means of gelatine, which also forms the bottom of the cells or divisions, the box being provided with a cover having its inner side coated with gelatine, so that when the cover is in place the gelatine will rest upon the edges of the gelatine forming the divisions or cells of the box, and thereby nearly or quite hermetically seal up their contents.

25 In the accompanying drawings, Figure 1 is a perspective view of my device having the gelatine molded in a paper box, which may be of any size or shape. Fig. 2 is a modification, showing channels or long cells in the gelatine; and Figs. 3 and 4 are perspective bottom

30 views of the former used in molding the gelatine into the forms shown respectively in Figs. 1 and 2.

A represents a box, preferably of paper, capable of holding one hundred capsules, and into this box a sufficient quantity of gelatine is poured to form the walls of the cells, and to form the interior walls of the box. After the gelatine has been poured into the box a former,

40 C, provided with cubes b or ribs c, having rounded surfaces is also placed in the box, the cubes or ribs causing the gelatine to rise between the cubes or ribs, so as to form walls around them of even height with the sides of the paper box. When the gelatine has become sufficiently stiff or set to allow the walls of the cell to stand alone the former is removed.

In order to especially adapt the box for car-

rying capsules or gelatine-covered pills without danger of breaking from the jarring incident to transportation, the gelatine is kept soft by being mixed with glycerine or any other of the known ingredients which would prevent it from becoming hard. By mixing the gelatine with a little glycerine, the amount being regulated by the consistency of the gelatine, it leaves the mass of sufficient stability to retain the form required for the walls of the cells and the lining of the box, and yet forms soft chambers for the capsules or pills.

The box thus made will keep its contents from mold and also from becoming hard, these results being obtained by the tight fit obtained between the soft gelatine on the cover and the soft gelatine divisions and walls forming the cells.

I do not in this application make claims to the process of or the dies for making the box as described, as these features form the subject-matter of a separate application, Serial No. 53,650.

I am aware of the Patent No. 84,972, and I do not claim a pill-box lined with a composition of paper-pulp molded into shape to form cavities; neither do I claim a mercury-package consisting of a strip of hard rubber having a series of cells to hold the mercury.

What I do claim is—

1. A box the bottom, sides, and ends of which are lined with gelatine subdivided into separate cells by means of division-walls made of the same material, substantially as described.

2. A box lined with soft gelatine having divisions to form cells, substantially as described.

3. A box lined with gelatine molded to form recesses and mixed with glycerine to keep it soft, substantially as described.

4. A box lined with soft gelatine molded to form separate cells having division-walls of the same height as the box, in combination with a cover, the inner side of which is also coated with soft gelatine, substantially as described.

P. CAUHAPÉ.
